UNITED STATES PATENT OFFICE.

RENÉ BILLARD, OF LE HAVRE, FRANCE.

INTERNAL-COMBUSTION ENGINE.

Application filed October 17, 1922. Serial No. 595,175.

To all whom it may concern:

Be it known that I, RENÉ BILLARD, a citizen of the French Republic, residing at No. 24 Rue Voltaire, Le Havre (Seine-Inférieure), France, have made certain new and useful Improvements in Internal-Combustion Engines, of which the following is a specification.

This invention relates to internal combustion engines and has for its object to provide a simple and effective means of operating the fuel pump for injecting fuel to the engine.

The invention further consists in the improvements hereinafter described and more particularly pointed out in the claims.

This invention will now be described more fully with reference to the accompanying drawings in which:

20 Figure 1 is a front elevation, partly in section, of an improved two-stroke cycle internal combustion engine constructed according to this invention.

Figure 2 is a vertical cross section of the 25 improved engine; and

Figure 3 is a partial sectional view of a detail.

In the illustrated example the improved 30 two-stroke cycle internal combustion engine comprises a cylinder 1 cooled by circulation of water or air and cooling ribs, with admission and exhaust ports.

In this cylinder there works a piston 2 provided with packing rings for making a 35 tight joint between the piston and the cylinder. Attached to the piston 2 is a connecting rod 3 sliding in a jointing member 4 fitted in a distributor 5. This distributor 5, preferably of cylindrical form, is moved by 40 the action of the motion of the connecting rod 3 in a baseplate 6 provided with suction ports 7 for sucking air or gas into the piston 2 which is open at its lower end, and also with delivery ports 8 for delivering said 45 air or gas into a receiver 9 and thence into the cylinder 1.

An injection pump 12, if required, is 50 driven by means of a small rod 10 acting as a plunger fixed in the longitudinal axis of the distributor 5, and abutting with its outer end against a lever 11 which drives the injection pump 12 directly. A pipe 13 connects the pump 12 to the top of the cylinder 1 for the purpose of allowing of the injection 55 of the carburetting medium into the

said cylinder by means of a spreader jet 14. The latter may be arranged at any desired point in the cylinder. The stroke of the injection pump 12 may be regulated for example by means of a regulating cam 15 acting 60 through the medium of the lever 11, or in any other manner.

The improved two-stroke cycle internal combustion engine thus constituted, operates 65 in the following manner:

It is assumed that the engine has started, and that the piston is rising from its lower dead centre. The resulting suction caused on the underside of the piston will act to suck-in the air or gases through the port 7 70 which has just been uncovered by the distributor 5. This suction continues until the piston is approaching the end of its up-stroke by which time the distributor 5 has closed the port 7 and uncovered the port 8. 75

During its down-stroke the piston forces the gases contained between it and the base-plate 6 (in which the distributor 5 and the jointing member 4 are fitted in a gas-tight manner) into the collector 9. As the piston 80 approaches the end of its down-stroke, it uncovers the exhaust port, and almost simultaneously the admission port through which the air or gases stored in the collector 9 pass into the cylinder. The same phenomena are 85 repeated at the lower end of the down-stroke of the piston.

At the same time as the distributor 5, operated by the connecting rod 3, has opened or closed at the proper times the ports 7 and 8, the plunger 10 has, through the medium of the lever 11, operated the injection pump 12 which (by reason of the predetermined movements) has injected the proper charge of carburetting medium through the spray- 95 er into the engine cylinder. The amount of this injection is controlled by means of the cam 15 which may be operated by hand or by a governor or in any other manner.

The engine also comprises an ignition apparatus, consisting for instance, of a magneto and sparking plug, or of a hot cylinder head, or other device for causing at the proper time the ignition of the carburetted mixture contained in the cylinder. 100

The improved engine may comprise any number of cylinders (one, two, three, four, five, six, etc.,) the collector 9 being designed, in the case of a plurality of cylinders, to distribute equally the charges of air or gas to 110

be admitted into the cylinders, and being capable also of serving as a reservoir for those gases.

The improved engine need not comprise 5 an injection pump, but may simply have a carburettor for delivering the carburetted gases. In such a case this carburettor may be mounted on the base-plate 6 near the admission port 7.

10 What I claim is:—

1. In an internal combustion engine having a cylinder and piston, a sliding member slidable at right angles to the axis of said cylinder, a connecting rod passing through 15 said sliding member and imparting thereto a reciprocating movement, and a fuel pump operated by the reciprocating movement of said sliding member, as set forth.

2. In an internal combustion engine having 20 a cylinder and a piston, a sliding member slidable at right angles to the axis of said cylinder, a connecting rod passing through a hole in said sliding member, a bell crank lever operated by said sliding member, and a fuel injection pump actuated by said bell crank lever, as set forth.

3. In an internal combustion engine having 25 a cylinder, piston, connecting rod and crank case, a base plate separating the cylinder from the crank case, a sliding member in said base plate, a gas tight joint in said sliding member through which the connecting rod passes, a bell crank lever actuated by said sliding member, a fuel injection 35 pump, and a plunger in said fuel pump operated by said bell crank lever.

4. In an internal combustion engine working on the two stroke cycle having cylinders, pistons, and a crank case, the combination 40 comprising a distributor for each cylinder having two ports therein, a sliding member situated in said distributor, a sleeve mounted in said sliding member adapted to oscillate about an axis at right angles to the axis of 45 the cylinder, a connecting rod sliding in said sleeve, a fuel pump actuated by the movement of said sliding member, and a collector common to all the cylinders and communicating with one of the ports in each distributor for receiving the air under pressure, 50 as set forth.

5. In an internal combustion engine working on the two stroke cycle having cylinders, pistons, and a crank case, the combination comprising a distributor for each cylinder having two ports therein, a sliding member situated in said distributor, a sleeve mounted in said sliding member, a cylindrical joint member mounted in said distributor into which said sleeve fits so as to oscillate 55 about a transverse axis, a connecting rod sliding in said sleeve, a fuel pump actuated by the movement of said sliding member, and a collector common to all the cylinders and communicating with one of the ports in each distributor for receiving the air under pressure, as set forth.

6. In an internal combustion engine working on the two stroke cycle having cylinders, pistons, and a crank case, the combination 70 comprising a distributor for each cylinder in the form of a fixed cylindrical tube having two ports therein one end of said tube being open to the atmosphere, a collector in communication with the other end of said 75 distributor tube, a sliding piston in said distributor tube, a connecting rod passing through an oscillating sleeve situated in said sliding piston, and a fuel pump actuated by the movement of said sliding piston, as set 80 forth.

7. In a two stroke internal combustion engine having a cylinder, piston, connecting rod and crank case, a base plate separating the cylinder from the crank case having suction and delivery ports therein leading to the interior of the piston, a receiver communicating with said delivery port and with the cylinder, a sliding member operated by the connecting rod in said base plate for 85 opening and closing said ports, a gas tight joint situated in said sliding member through which the connecting rod passes, a fuel injection pump, a plunger in said fuel pump, a bell crank lever for actuating the fuel injection pump plunger, and means on said sliding member for actuating said bell crank lever.

In testimony whereof I have signed my name to this specification.

RENÉ BILLARD.
